UNITED STATES PATENT OFFICE.

SILAS ALVIN GENTRY, OF NASHVILLE, TENNESSEE.

GAS MIXER.

Application filed September 18, 1923. Serial No. 663,454.

To all whom it may concern:

Be it known that I, SILAS A. GENTRY, a citizen of the United States, residing at Nashville, in the county of Davidson and 5 State of Tennessee, have invented a new and useful Gas Mixer, of which the following is a specification.

This invention relates to an attachment for internal combustion engines, the primary 10 object of the invention being to provide novel means for supplying heated air to the charge entering the intake manifold after the charge has passed from the carburetor.

Another 15 object of the invention is to provide a device of this character including a nozzle of a construction to be readily and easily secured to the usual internal combustion engine construction, the nozzle being such as to direct the heated air through the 20 charge at an angle with respect to the path of travel of the charge.

With the foregoing and other objects in view which will appear as the description 25 proceeds, the invention resides in the combination and arrangement of parts and in the details of construction hereinafter described and claimed, it being understood that changes in the precise embodiment of the invention herein disclosed, may be made within 30 the scope of what is claimed, without departing from the spirit of the invention.

Referring to the drawings:

Figure 1 is an elevational view disclosing 35 the attachment as installed on an internal combustion engine.

Figure 2 is a fragmental sectional view disclosing the relation of the nozzle with respect to the intake manifold.

Figure 3 is a sectional view on line 3—3 40 of Figure 2.

Figure 4 is an enlarged elevational view of the nozzle portion.

Referring to the drawings in detail, the reference 45 character 5 designates the intake manifold of an internal combustion engine, which is formed with the usual flange 6 at the intake end thereof, which flange cooperates with the flange 7 formed at the upper end of the carburetor pipe 8 for clamping the nozzle of the attachment in position.

The nozzle is indicated generally by the reference character 9 and embodies a head formed with openings 10 to receive securing

bolts 11 that also pass through the flanges 55 6 and 7 to secure the nozzle in position. A central opening 12 is formed in the nozzle, which opening registers with the intake manifold 5 and pipe 8 so that a charge passing from the carburetor which is in communication with the pipe 8 and which has been omitted in the present showing, may pass to the intake manifold in the usual manner.

A wall 13 is formed across the lower portion 65 of the opening 12 and has a cut out portion 14 in one surface thereof, which cut out portion has communication with the bore 15 through the openings 16, whereby air passing through the bore 15 may enter 70 the intake manifold 5, through the openings and at an angle with respect to the passage of travel of the charge from the pipe 8, to the end that the air is thoroughly mixed with the charge.

The reference character 17 designates a valve body in which is positioned a controlling 75 valve 18 for controlling the passage of air to the nozzle proper, the communication between the valve body 17 and nozzle being 80 made through the pipe 19.

Coiled around the exhaust pipe 20 is a pipe 21 that has one end thereof connected with the valve body 17 at 22, the opposite end of the pipe 21 being disposed adjacent 85 to the forward end of the exhaust manifold 22, while the portion of the pipe between the coiled portion thereof and open end 23 is disposed on the exhaust manifold 22 as clearly shown by Figure 1, so that the heat 90 from the exhaust manifold 22 will be directed to the pipe which in turn will heat the air passing therefrom.

The valve 18 is formed with an arm 24 that has connection with the rod 25 that is 95 employed for operating the valve 18 through the medium of the connecting link 26 and arm 27 secured to the lower end of the rod 25.

It might be further stated that the upper 100 end of the rod 25 is disposed in proximity to the steering wheel of the motor vehicle, whereby the same may be readily and easily manipulated by the person operating the vehicle.

In the use of the device the valve member 18 is operated to allow a predetermined amount of air to be drawn through the pipe

21 to increase the efficiency of the engine and at the same time reduce the fuel consumption to the minimum.

I claim:—

- 5 In a device of the character described, a nozzle adapted to be secured at one end of an intake manifold of an internal combustion engine, said nozzle including a body portion having a bore formed therein, said 10 body portion having a cut out portion forming a compartment opening towards the forward portion of the body portion, and defining an upper partitioning wall, said body portion having a plurality of openings estab-

lishing communication between the bore and 15 compartment to direct heated air to the manifold, and said body portion having an opening to permit the passage of fuel there-through, at a point adjacent to the compartment.

20 In testimony that I claim the foregoing as my own, I have hereto affixed my signature in the presence of two witnesses.

SILAS ALVIN GENTRY.
